10 Claims. (Cl. 117—2)

This invention relates to operations and apparatus in which twist is imparted to textile threads, e. g. to crêpe twisting operations and apparatus.

5 According to the invention a thread that is to receive twist is wetted and then subjected to the action of steam at a point where the thread is receiving twist, the wetting being effected by means of a rotatable roller into contact with the periphery of which the thread comes to pick up a controlled amount of moisture.

In order that the action of the twisting device shall extend over that part of the length of the thread which is being subjected to the action 15 of the steam, it is important that the thread should undergo no material deviation from its path or be otherwise subjected to material restraint between the twisting device and the end of the steaming zone remote from the twisting device. Thus, in the case where the twist is applied to a thread proceeding from a delivery package, the roller serving to wet the thread between the twisting device and the steaming zone should only make light contact with the thread 20 so as not to prevent the twist imparted by the twisting device from running past the roller into the steaming zone. When, however, the twist is being applied at a take-up package, e. g. by a ring-spinning device, it is of less importance 25 whether the wetting roller preceding the steaming zone, which in this case is located between the roller and the twisting device, causes any substantial deviation or not of the thread.

The roller may be positively driven so as to 30 pick up water from a trough into which it dips and apply it at a steady rate to the thread depending upon the speed of rotation of the roller. The roller may, however, be lightly pivoted so as to be rotated by contact with the thread it- 35 self.

If desired the roller may be provided with a layer of absorbent material to assist in carrying the water to the thread, but in this case it is important that the material should not be of loose 40 structure, or contain any protruding fibers, since the thread receiving the twist might become entangled with the covering.

A preferred form of roller specially adapted to carry a predetermined amount of liquid to the 45 thread has an uncovered surface provided with a shallow groove. This groove has a width preferably only slightly in excess of the thickness of the thread and a depth sufficient to enable the desired quantity of moisture to be elevated. The 50 twisted thread enters the groove and so receives

the moisture picked up from the trough by the rotation of the roller. The contact between the thread and the liquid-carrying roller is very light, so that twist is not restrained from running past the roller into the steaming zone. 5

By way of example two forms of apparatus according to the invention will now be described in greater detail with reference to the accompanying drawing in which—

Fig. 1 is a side elevation of a twisting device 10 provided with moistening means according to the invention;

Fig. 2 is a front elevation of the upper part of Fig. 1; and

Fig. 3 shows an alternative form of the moistening apparatus as shown in Fig. 2. 15

A package 1 is mounted on a twisting spindle 2 which is rotated by means of a suitable wharf 3. Yarn 4 is drawn from the package 1 and passes through a thin ring 5 disposed between two flanges 6 on the spindle 2 before proceeding upwards to a balloon guide 7 of stainless steel. From the balloon guide 7 the yarn passes through a steam pipe 8, which, as indicated in Fig. 2, serves a bank of spindles 2. The steam pipe 8 is provided with offset chambers 9, one for each of the spindles 2, as is described in U. S. application S. No. 25,054, filed 5th June, 1935, apertures 10, 11 being provided in the bottom of the pipe 8 and the top of the chamber 9, respectively, 20 through which the thread passes. From the aperture 11 the thread passes to a traversing guide 12 mounted on a traversing bar 13, which guide traverses the yarn on a bobbin 14 driven with constant peripheral speed by means of a driving drum 15. 30

Surrounding the offset chamber 9 is a ring 16 secured thereto by means of a knurled screw 17. The ring forms part of a bracket 18 which carries at its lower end a vessel 19 adapted to contain water or other liquid suitable for moistening the yarn 4. The balloon guide 7 is carried on the end of the vessel 19. On the sides of the vessel 19 are lugs 20 for carrying a moistening roller 21. The roller 21 is mounted on a spindle 22 having pointed ends which fit into conical recesses in the ends of the screws 23 passing through the lugs 20 and fixed in position by means of lock nuts 24. In the middle of the 45 surface of the roller 21 is a circumferential groove 25 in which the thread 4 runs while passing from the balloon guide 7 to the steam pipe 8. The height of the bracket 18 and of the parts carried thereby may be adjusted by loosening the screw 55

17, and raising or lowering the ring 16 on the offset chamber 9.

By the means described above the thread 4 is twisted by the rotation of the spindle 2 and is twisted by the rotation of the spindle 2 and 5 the bobbin 1, and, on account of the trapping means 5, 6 mounted on the spindle, and the direct path of the thread 4 from said trapping means to the interior of the steam pipe 8 and chamber 9, twist enters the yarn at a point inside the steam pipe and chamber. The contact 10 made between the thread 4 and the roller 21 is sufficiently light to allow the twist imparted by the rotation of the spindle 2 to enter the yarn at a point beyond said roller.

15 In Fig. 3 an alternative form of moistening roller is illustrated in which the roller 21, instead of being grooved as in Figs. 1 and 2, is provided with a covering of felt 26. Here, again, the contact between the thread 4 and the felt 20 26 on the periphery of the roller 21 is light enough to permit the twist to enter the yarn at a point beyond the roller.

Having described our invention what we desire to secure by Letters Patent is:—

25 1. In an operation involving imparting twist to a travelling thread, the steps of subjecting the thread to the action of steam at a point where said thread is receiving twist and, before said thread reaches said point, running said 30 thread over a moving wetted surface so as to moisten the thread before steam is applied to it.

2. In an operation involving imparting twist to a travelling thread, the steps of drawing the thread from a rotating package, moistening said 35 thread by running it over a moving wetted surface, contact between said thread and said surface being light enough to permit twist to be imparted by the rotation of said package to said thread at a point beyond said surface, and subjecting the moistened thread to the action of steam at said point, i. e., where the thread is receiving twist.

3. Apparatus in which twist is imparted to a thread, said apparatus comprising means for 45 imparting twist to a travelling thread, means for applying steam to said thread at a point where said thread is receiving twist, a rotatable roller over which said thread is caused to run in passing to said applying means, and means for wetting the surface of said roller in order to moisten 50 the thread before steam is applied to it.

4. Apparatus in which twist is imparted to a thread, comprising a twisting spindle, means for applying steam to a thread leaving said twisting 55 spindle, said means by its disposition relative to said twisting spindle being adapted to apply steam to the thread at a point where the thread is receiving twist, a rotatable roller over which said thread is caused to pass between said 60 twisting spindle and said applying means, and means for wetting the surface of said roller so as to moisten the thread passing over it, said roller being adapted to make with said thread a contact light enough to permit the twist imparted by said twisting spindle to enter the thread at a point beyond said roller.

5. Apparatus in which twist is imparted to a thread, comprising a twisting spindle, means for applying steam to a thread leaving said twisting 70 spindle, said means by its disposition relative to said twisting spindle being adapted to apply steam to the thread at a point where the thread is receiving twist, a rotatable roller over which

said thread is caused to pass between said twisting spindle and said applying means, the surface of said roller having a circumferential groove therein, and means for wetting said roller so as to moisten the thread by the moisture held in said groove, said roller being adapted to make with said thread a contact light enough to permit the twist imparted by said twisting spindle to enter the thread at a point beyond said roller. 5

6. Apparatus in which twist is imparted to a 10 thread comprising a twisting spindle, means for applying steam to a thread leaving said twisting spindle, said means by its disposition relative to said twisting spindle being adapted to apply steam to the thread at a point where the thread is receiving twist, a rotatable roller over which said thread is caused to pass between said twisting 15 spindle and said applying means, a felt covering for the periphery of said roller, and means for wetting said roller so as to moisten the thread by the moisture held in said covering, said roller being adapted to make with said thread a contact light enough to permit the twist imparted by said twisting spindle to enter the thread at a point beyond said roller.

7. Apparatus in which twist is imparted to a thread, said apparatus comprising a twisting spindle, means for applying steam to thread leaving said twisting spindle, said means by its disposition relative to said twisting spindle being 30 adapted to apply steam to the thread at a point where the thread is receiving twist, a bracket carried upon said applying means, a rotatable roller mounted in said bracket, over which roller the thread is caused to pass between said twisting 35 spindle and said applying means, said roller having a circumferential groove in its surface, a vessel carried by said bracket into which said roller is adapted to dip, whereby said groove is fed with moisture contained in said vessel and said thread is moistened by the moisture held in said groove, said roller being adapted to make with said thread a contact light enough to permit the twist imparted by said twisting spindle to enter the thread at a point beyond said roller. 40

8. Apparatus in which twist is imparted to a thread, said apparatus comprising a twisting spindle, means for applying steam to thread leaving said twisting spindle, said means by its disposition relative to said twisting spindle being 50 adapted to apply steam to the thread at a point where the thread is receiving twist, a bracket carried upon said applying means, a rotatable roller mounted in said bracket over which roller the thread is caused to pass between said twisting 55 spindle and said applying means, a felt covering for the periphery of said roller, a vessel carried by said bracket into which said roller is adapted to dip whereby said covering is fed with moisture contained in said vessel and said thread is moistened by the moisture held in said covering, said roller being adapted to make with said thread a contact light enough to permit the twist imparted by said twisting spindle to enter the thread at a point beyond said roller. 60

9. Apparatus according to claim 7, wherein the bracket carries a balloon guide for said twisting spindle. 65

10. Apparatus according to claim 8, wherein the bracket carries a balloon guide for said twisting spindle. 70
